UNITED STATES PATENT OFFICE.

EDWIN P. GAYLORD, OF ROCHESTER, NEW YORK.

VEHICLE-CLEANING DEVICE.

No. 895,551.

Specification of Letters Patent.

Patented Aug. 11, 1908.

Application filed October 5, 1906. Serial No. 337,564.

To all whom it may concern:

Be it known that I, EDWIN P. GAYLORD, of Rochester, in the county of Monroe and State of New York, have invented certain new and useful Improvements in Vehicle-Cleaning Devices; and I do hereby declare the following to be a full, clear, and exact description of the same, reference being had to the accompanying drawings, forming a part 10 of the specification, and to the reference-numerals marked thereon.

My present invention relates to improvements in devices of the kind particularly adapted to the cleaning of vehicles, and for 15 similar purposes, and it relates more especially to that class of cleaning devices having a cleaning medium such as a sponge, arranged to be supplied continuously or from time to time with liquid from a suitable 20 source, and the object of the present invention is to provide a device of this kind having novel devices for securing the sponge or other cleaning medium in operative position, the securing means being so constructed and arranged 25 as to enable the sponge to be readily attached to and detached from the device, and, which, when in operative position, will be automatically secured and held from displacement, the sponge being so arranged relatively 30 to the source of liquid supply that the liquid will be confined to the sponge, enabling the device to be manipulated without the danger of soiling the clothes of the operator.

To these and other ends the invention consists 35 in certain improvements and combinations of parts, all as will be hereinafter more fully explained, the novel features being pointed out in the claims at the end of the specification.

40 In the accompanying drawings: Figure 1 represents a longitudinal section of a fountain cleaning device constructed in accordance with my invention, the sponge or cleaning medium being shown secured in operative position. Fig. 2 represents an elevation of the device with the follower retracted to enable the sponge to be applied or removed therefrom, and Fig. 3 represents a top plan view of the device shown in Figs. 1 and 2; 45 and Fig. 4 represents a longitudinal section of another embodiment of the invention.

Similar reference numerals in the several figures indicate similar parts.

The present embodiment of the invention 50 is particularly adapted for use in washing and cleaning carriages and automobiles, and

for similar purposes, and it comprises generally a nozzle 1 which serves as a shank or handle for the manipulation of the device, having a coupling member 2 arranged at one end 60 thereof and adapted to be connected to an ordinary hose leading from a suitable source of liquid supply, the opposite end of this nozzle having a discharge 3 from which the liquid supplied to the nozzle is adapted to be 65 projected, this discharge being preferably provided with a sprinkler in the form of a perforated head or strainer 4 for spreading the liquid into a spray. The exterior of this nozzle has a portion preferably of substantially uniform diameter to form a guide way extending longitudinally between the discharge end and the coupling member 2 of the nozzle, and fitted over this nozzle is a follower 5 having a hub 6 which is guided on 70 and arranged to operate longitudinally on the guide way of the nozzle, a rib 7 extending longitudinally of the guide and serving as a key to coöperate with a corresponding recess 8 formed in the hub of the follower to prevent 75 rotation thereof as it operates in a direction axially of the nozzle. This follower embodies, in the present instance, a face plate 9, preferably of metal or other rigid material, dished in form and having a cup 10 fitted 80 against its rear surface, this cup being preferably composed of soft rubber or other flexible material, having its flanged edge surrounding, and turned toward the direction of discharge of the nozzle in order that it may 85 coöperate with the sponge or other cleaning medium as a support therefor and as a packing, to prevent relatively rearward or lateral escape of the liquid discharged from the nozzle, and also serving to protect the varnished 90 or painted parts of the vehicle from damage by contact with the metallic parts of the device. This cup is attached to the follower plate by means of hollow rivets 11, the latter being extended through apertures in the 100 plate 9 and headed on the forward surface thereof and extending through the rubber cup and headed on the rear surface of the latter. This follower by reason of its movement axially of the nozzle, serves to operate 105 the securing devices which engage and release the sponge, and these securing devices in the present form of the invention, comprise a set of gripping members 12, each of these members being composed of a pair of 110 divergently-arranged, branched arms which extend through the hollow rivets 11 on the

follower as operating guides, and are provided at their free ends with suitably shaped claws or gripping fingers 13, the intermediate bend of these arms being pivoted in the lugs 5 or ears 14 formed on the coupling member or other relatively fixed part of the nozzle.

The radial distance between the axis of the nozzle and the guides formed by the rivets 11 on the follower, is greater than the distance 10 between the pivotal points of the securing members, and said axes, so that when the follower occupies a position similar to that shown in Fig. 1, the claws or gripping fingers on the securing members will be in approxi- 15 mated position, serving to firmly secure the sponge mop or other cleaning medium in co-operative relation with the discharge end of the nozzle. However, when the follower is retracted or drawn into the position shown in 20 Fig. 2, the divergent relation of the arms of the gripping devices will cause the latter to be spread or separated, so that the cleaning medium may be conveniently applied or removed relatively to the nozzle after the follower 25 has been appropriately operated.

In order to enable the device to be handled readily, it is preferable to provide automatic means for operating the gripping members to clamp and hold the cleaning 30 medium automatically, and this is accomplished in the present instance by means of a helical spring 15 which encircles the exterior of the nozzle, and having one end resting against the shoulder formed by the hose 35 coupling member while its opposite end bears against the follower, the compression of the spring serving to normally operate the follower toward the discharge end of the nozzle to proximate or draw together the 40 gripping fingers, the action of this spring serving to retain the follower in such a position and thereby prevent disengagement or displacement of the sponge or cleaning device relatively to the nozzle. The cup on 45 the follower at this time will also obtain a firm seating against the adjacent surface of the sponge to form a liquid seal that will confine the liquid to the inclosed area of the sponge so that it may be absorbed thereby, and the flange of the cup is so directed that 50 the water cannot splash rearwardly or toward the operator. As the pressure acting on the follower is a yielding one, it enables the device to securely clamp mops, sponges or 55 other cleaning devices of different sizes, and at the same time, the protecting cup will be pressed into co-operative relation with the cleaning medium with a yielding pressure, thereby enabling the cup to seat itself prop- 60 erly, and the spring of course serves the dual purpose of locking the securing members in co-operative relation with the cleaning me- 65 dium, as well as holding the cup and follower firmly seated against the cleaning medium.

In the present embodiment of the invention the mop-securing devices are shown and described in combination with a nozzle, the latter serving to create a flow of water through the sponge or mop during the cleaning operation, but the invention is not necessarily limited in this respect. 70

The sponge or mop-engaging hooks or fingers in the present invention have their engaging prongs bent at an acute angle relatively to the supporting arms, forming bends in the hooks of sufficient size or capacity to receive a considerable portion of the sponge or mop when the hooks are in operated or engaging position by reason of the space thus 75 provided between the bent portions of the hooks and the follower, and this not only enables the sponge to be firmly secured in place, but the increased amount of sponge surrounding the discharge end of the nozzle 80 serves to form a packing to prevent the escape of water in rear of the sponge. 85

In that form of the invention just described, the discharge end of the nozzle is provided with a sprinkler head which insures thorough saturation of the sponge or 90 mop, and at the same time enables the device to be employed as a sprayer by omitting the sponge or mop, but instead of using a discharge of the form just described, a nozzle 95 of the form shown in Fig. 4 may be employed, the discharge end of the nozzle tube having a double conical valve seat 16 fitted therein, and having an axially adjustable valve rod 17 provided with a conical valve 100 head 18 adapted to coöperate with the rear conical valve seat to control the flow of water through the nozzle, a spreading head 19 being formed on the valve head opposite to the forward conical valve seat for spreading or 105 spraying the water so as to thoroughly saturate the sponge, the valve head serving to restrain the flow of water to the latter.

The valve rod may be operated in any convenient manner, the operating means shown 110 in the present form of the invention embodying a shell 20 secured to the rear end of the nozzle and having an internal thread therein to receive and coöperate with the corresponding threads on the cylindrical 115 extension of the coupling member 21, to which the rod 17 is secured, relative rotation of the coupling member and the nozzle member serving to operate the valve stem and its valve head longitudinally relatively to the 120 valve seat to increase or decrease the amount of water passing through the valve, and the regulation of the water in this manner is advantageous, as it effects a saving in the 125 amount of water consumed and insures the supply of the proper amount of water to the sponge, and by arranging the water regulating device as a part of the washer, the device is self contained, so that it may be conveniently manipulated. The gripping 130

members 12 in this embodiment are fixed to the shank by being pivoted to a collar which is brazed or otherwise secured to the inner end of the shank.

5. I claim as my invention:

1. In a cleaning device, the combination with a tubular shank having a discharge end, a plurality of movable fingers surrounding the shank and fixed thereto at one end, of an operating member coöperating with the fingers and movable longitudinally of the shank to adjust the opposite extremities of said fingers relatively to each other, said member being formed and arranged to coöperate with a 10 mop held by the fingers and prevent a rearward discharge from the mop.

2. In a cleaning device the combination with a shank, a plurality of movable fingers disposed around the shank and fixed thereto 20 at one end, of an operating member movable longitudinally on the shank and coöperating with the fingers to move them relatively in an outward direction when adjusted toward their fixed ends and to move them inwardly 25 when adjusted in the opposite direction and means for normally moving the member in a direction away from the fixed points of the fingers.

3. In a cleaning device, the combination with a tubular shank having a discharge end, a plurality of fingers extending longitudinally of and pivoted to the shank, of an operating member coöperating with the fingers at the discharge end of the shank to hold them in 35 proximity thereto, said member being adapted to be adjusted longitudinally of the shank to move the fingers outwardly and a spring normally operating the member in one direction.

40. 4. In a cleaning device, the combination with a tubular shank having a discharge at one end, of a combined guard and follower mounted to move longitudinally thereof to prevent a rearward discharge from the nozzle, 45 and gripping members on which the follower slides to operate them, having portions adapted to coöperate with a mop to secure the latter in position at the discharge end of the shank.

50. 5. In a cleaning device, the combination with a nozzle, and a set of gripping members attached to relatively fixed portions of the nozzle and having portions adapted to co-operate with a mop to secure it in operative position on the discharge end of the nozzle, of a follower movable on and longitudinally of the nozzle and coöperating with said gripping members to operate them relatively toward and from each other.

60. 6. In a cleaning device, the combination with a nozzle, and a set of gripping members thereon having portions adapted to coöperate with a mop to secure it in position at the discharge end of the nozzle, of a follower 65 coöperating with the gripping members and

movable axially of the nozzle to operate them and having a cup thereon arranged to surround the discharge opening of the nozzle and to rest against the mop.

7. The combination with a nozzle, and a 70 set of gripping members thereon having portions adapted to coöperate with a mop to secure it in position at the discharge end of the nozzle, of a follower operable in a direction axially of the nozzle and coöperating 75 with the said members to engage and disengage them relatively to the mop, and a cup of soft or yielding material secured to the follower for protecting the metallic parts of the device and serving to confine the liquid 80 discharging from the nozzle.

8. The combination with a nozzle, and gripping members thereon having portions adapted to coöperate with a mop to secure it in position at the discharge end of the 85 nozzle, of a follower movable longitudinally of the nozzle and coöperating with said members for operating them to secure the mop when the follower is operated toward the discharge end of the nozzle, a cup carried by 90 the follower and arranged to coöperate with the back of the mop, and a spring encircling the nozzle and normally operating to move the follower toward the discharge end of the nozzle. 95

9. The combination with a nozzle having a guiding surface formed, on its exterior, and a set of gripping members carried by the nozzle having divergently-extending operating arms, and provided with portions adapted to coöperate with a mop to secure it in operative position on the discharge end of the nozzle, of a follower mounted to operate longitudinally on the guides of the nozzle, a cup of soft material carried by the follower, 100 and hollow rivets extending through the said cup and secured to the follower and coöperating as guides with the operating arms of the gripping members for proximating and separating the latter as the said follower is operated. 110

10. The combination with a nozzle having a guiding surface thereon, and a follower mounted to reciprocate on the guiding surface in a direction longitudinally of the nozzle, of gripping members each embodying a wire bent intermediately to form a pair of divergently-arranged branch arms provided with claws at their ends for engaging a mop, the intermediate portion of the wire being 115 pivoted to a relatively fixed portion of the nozzle, and the branch arms of the members coöperating with the follower, operation of the latter on the nozzle serving to proximate and separate the claws on the said members. 120 125
